CULTIVATOR ATTACHMENT

Walter M. Reynolds, San Antonio, Tex.

Application January 8, 1938, Serial No. 184,061

8 Claims. (Cl. 97—198.1)

This invention aims to provide novel means whereby soil-engaging elements may be assembled with the beams of a cultivator, in adjusted positions.

5 It is within the province of the disclosure to improve generally and to enhance the utility of devices of that type to which the present invention appertains.

With the above and other objects in view, 10 which will appear as the description proceeds, the invention resides in the combination and arrangement of parts and in the details of construction hereinafter described and claimed, it being understood that changes in the precise embodiment of the invention herein disclosed, 15 may be made within the scope of what is claimed, without departing from the spirit of the invention.

In the accompanying drawings:

20 Fig. 1 shows in side elevation, a device constructed in accordance with the invention;

Fig. 2 is an end elevation;

Fig. 3 is a perspective view disclosing one of the brackets;

25 Fig. 4 is an elevation showing a modified arrangement;

Fig. 5 is a side elevation showing a still further modified arrangement;

Fig. 6 is an end view of the structure depicted 30 in Fig. 5;

Fig. 7 is a top plan of the structure shown in Figs. 5 and 6;

Fig. 8 is an enlarged sectional view showing a portion of the structure appearing in Figs. 5, 6 35 and 7;

Fig. 9 is a perspective view showing the supplemental beam.

In Figs. 1 and 2, cultivator beams are shown at 1. Hangers 2 are provided, and each hanger 40 includes a first arm 3 and a second arm 4 arranged at right angles to the first arm 3, the hangers 2 being twisted, as shown at 5, at the juncture between the arms 3 and 4, so that, so far as major transverse dimensions are concerned, the arms 3 and 4 are in planes at right angles to each other. The hangers 2 need not be of the precise construction shown and described, especially as to the twist shown at 5, and the hangers may be of any preferred form in 45 which the general rectangular relation between the arms 3 and 4 is substantially preserved. By means of clips 6 and securing elements 7, the first arms 3 of the hangers 2 are secured for vertical adjustment to the cultivator beams 1.

50 Brackets are provided, and one of the brackets

is shown in Fig. 3, the bracket being designated by the numeral 8. Each bracket comprises a first or vertical depending flange 9 and a second or horizontal flange 10. The flanges 10 of the brackets 8 on the respective beams project outwardly in opposite directions with respect to the median plane of the implement. There are spaced lines of openings 11 in the flange 9, and spaced lines of openings 12 in the flange 10. By means of securing elements 14, mounted in one of the lines of openings 11, the second or horizontal arms 4 of the hangers 2 are connected to the second or horizontal flanges 10 of the brackets 8. Securing elements 15, mounted in any one of the lines of openings 12, attach the horizontal shanks 16 of soil-engaging elements 17 to the flanges 10 of the brackets 8. The securing elements 15 may be mounted in any of the lines of openings 12, and, thus, a horizontal adjustment between the soil-engaging elements 17 may be brought about. A vertical adjustment may be secured by shifting the first arms 3 of the hangers 2 in the clips 6. Figures 1 and 2 show one of the simplest applications of the invention.

In Fig. 4, parts hereinbefore described have 25 been designated by numerals previously used, with the suffix "a". The flanges 10a of the brackets 8a of the respective beams 1a project inwardly with respect to the median plane of the implement. Brackets 18, constructed like the 30 brackets 8 are provided. The vertical arms 19 of the brackets 18, corresponding to the arms 9a, are attached to the arms 9a by securing elements 20. The arms or flanges 21 of the brackets 18 extend outwardly, and to them the shanks of 35 soil-engaging elements 22 are secured, as shown at 23, by means of bolts or the like, mounted in the openings corresponding to the openings 12 of Fig. 3. It will be observed that an in and out horizontal adjustment of the soil-engaging elements 22 is possible. The arms 3a of the hangers nearest to the median plane of the implement are caused to extend upwardly instead of downwardly and the arrangement of parts is such that the soil-engaging element can work upon a ridge 24 45 of considerable height.

In Figs. 5, 6 and 7, parts hereinbefore described have been designated by numerals already used, with the suffix "b".

In this arrangement, the brackets 18b, corresponding to the brackets 18a are used, but they extend upwardly, instead of downwardly as in Fig. 4.

Extension bars 25 are provided and have countersunk openings 26 adapted to receive secu- 55

ing elements 27 which attach the extension bars 25 to the flanges 10b and 21b of the brackets 8b and 18b respectively. The extension bars 25 may project either rearwardly or forwardly, as shown 5 in Fig. 7, and the shanks 28 of the soil-engaging elements 29 are overlapped upon the extension bars 25 and are attached thereto by securing elements 30. Because the extension bars 25 may be made to project either forwardly or rearwardly, 10 the soil-engaging elements 29 may be spaced apart, longitudinally of the draft line, the extension bars 25 having openings 31 for the reception of the securing elements 30. A transverse adjustment of the soil-engaging elements 29 also is 15 provided, owing to the presence of the lines of openings 12b in the flanges 21b and 10b of the brackets 8b and 18b respectively.

It will be observed that numerous horizontal and vertical adjustments are possible in the positions of the soil-engaging elements, the arrangement of parts shown in Fig. 6 being of peculiar utility when the soil-engaging elements 29 must work in a hollow, the soil-engaging elements 22 of Fig. 4 being adapted to work on a ridge, and 25 the soil-engaging elements 17 of Fig. 2 being adapted to work on comparatively level ground.

What is claimed is:

1. In a device of the class described, a hanger comprising horizontal and vertical arms, means 30 for securing the vertical arm to a plow beam for vertical adjustment, a bracket having rectangularly disposed parts, means for attaching one of the rectangularly disposed parts of the bracket to the horizontal arm of the hanger, a soil-engaging element, and means for attaching the soil-engaging element to one of the rectangularly disposed parts of the bracket.

2. In a device of the class described, a hanger having a vertical arm and a horizontal arm, a bracket having rectangularly disposed parts, a securing member joining one part of the bracket to the horizontal arm of the hanger, a soil-engaging element, and means for connecting the soil-engaging element to one of said parts of the bracket.

3. A device of the class described, constructed as set forth in claim 2, and wherein the substantially horizontal part of the bracket has transversely spaced openings for the reception 50 of the securing member.

4. A device of the class described, constructed as set forth in claim 2, and wherein said means comprises a securing member connecting the soil-engaging element to the substantially horizontal part of the bracket.

5. A device of the class described, constructed as set forth in claim 2, and wherein said means comprises a securing member connecting the soil-engaging element to the substantially horizontal part of the bracket, said part having transversely spaced openings for the adjustable reception of the last-specified securing member.

6. In a device of the class described, a hanger having an upstanding arm and a substantially horizontal arm, a first bracket having a depending part and an inwardly extended substantially horizontal part, a securing member joining the substantially horizontal part of the bracket to the substantially horizontal arm of the hanger, a second bracket constructed like the first bracket, but inverted to comprise an upstanding part and an outwardly extended part, a securing member joining the depending part of the first bracket with the upstanding part of the second bracket, a soil-engaging element, and means for securing the soil-engaging element to the outwardly extended part of the second bracket.

7. In a device of the class described, upper and lower brackets, each comprising a horizontal part and a vertical part, means for connecting the vertical parts of the brackets together to permit an inversion of the lower bracket, thereby to dispose the horizontal part of the lower bracket higher than or lower than the horizontal part of the upper bracket, at the will of an operator, soil-engaging elements, and means for securing one soil-engaging element to the horizontal part of each bracket.

8. A device of the class described, constructed as set forth in claim 7 and wherein the last-specified means embodies extension bars whereon the soil-engaging elements are mounted, and means for securing the extension bars to the horizontal parts of the brackets, with one extension bar projecting forwardly and the other 45 extension bar projecting rearwardly, thereby to space the soil-engaging elements apart, longitudinally of the line of advance of the soil-engaging elements.

WALTER M. REYNOLDS. 50
